UNITED STATES PATENT OFFICE

116,132

DESIGN FOR AN ICON PROJECTOR OR SIMILAR ARTICLE

Arthur G. Dannell, Flushing, N. Y.

Application October 29, 1938, Serial No. 80,759

Term of patent 3½ years

To all whom it may concern:

Be it known that Arthur G. Dannell, a citizen of the United States, residing in Flushing, Long Island, in the county of Queens and State of New York, has invented a new, original, and ornamental Design for an Icon Projector or Similar Article, of which the following is a specification, reference being had to the accompanying drawing, forming a part thereof, wherein:

Fig. 1 is a top plan view of the icon projector or similar article showing the new design;

Fig. 2 is an elevational view of the icon projector or similar article showing my new design, and

Fig. 3 is a side view of the icon projector or similar article shown in Fig. 2.

I claim:

The ornamental design for an icon projector or similar article, as shown.

ARTHUR G. DANNELL.
